UNITED STATES PATENT OFFICE.

STUART A. COGSDILL, OF DETROIT, MICHIGAN, ASSIGNOR TO DETROIT REAMER
SALVAGE CO., OF DETROIT, MICHIGAN, A CORPORATION OF MICHIGAN.

REAMER.

1,214,649.

Specification of Letters Patent.

Patented Feb. 6, 1917.

Application filed March 18, 1916. Serial No. 85,023.

To all whom it may concern:

Be it known that I, STUART A. COGSDILL, a citizen of the United States of America, residing at Detroit, in the county of Wayne 5 and State of Michigan, have invented certain new and useful Improvements in Reamers, of which the following is a specification, reference being had therein to the accompanying drawings.

10 The invention relates to reamers and more particularly to a construction in which the reaming shell is detachable from the shank.

The invention has among the objects thereof to provide a construction of reamer 15 employing an expansible reaming shell by which the diameter of the expansible portion of the shell may be easily, quickly and accurately adjusted; to provide for rigidly clamping the expansible portions of the 20 reaming shell in their adjusted position.

25 Further, to provide a construction of reamer in which the centers are in permanent relation to each other.

Other objects of the invention will more 25 fully hereinafter appear.

The invention consists in the peculiar construction, arrangement and combination of parts as hereinafter set forth and as particularly pointed out in the claims.

30 In the drawings,—Figure 1 is a perspective view of the device embodying the invention; Fig. 2 is an enlarged, longitudinal, central section; Fig. 3 is a section on the line $x-x$ of Fig. 2.

35 Referring to the construction shown in Figs. 1 to 3 inclusive, A designates the shank of the reamer, having the usual tapered spindle B, and C is the reaming shell provided with a central bore D snugly fitting the rear portion of the tapering spindle. The inner end of the shell is provided with diametrically opposed recesses E for 40 engaging lugs F at the inner end of the spindle B. G is an integral collar upon 45 the shank A against which the inner edge H of the shell abuts.

The shell C is formed with a plurality of slits I, three being shown in the construction illustrated in the drawings. These 50 slits extend from the forward edge of the shell for a portion only of the length of the latter, the slits preferably being about half the length of the shell. The inner end of

the shell is therefore rigid. The blades or cutting edges a are also formed as a unitary 55 part of the shell.

With a reamer it is very necessary to have the diameter of the cutting portions of the shell exceedingly accurate. The cutting portions however, wear down, and unless some means is provided for expanding the cutting portions of the shell, after it has become worn it cannot again be used for reaming openings having a diameter of the original diameter of the shell. With the 60 construction embodying the invention the expansible portions of the shell not only permit adjusting the diameter of the cutting edges to a high degree of nicety, but also allow the cutting portions to be ex- 65 panded after they have become worn, so as to restore their cutting edges to the original diameter.

Thus as illustrated, upon the end of the spindle B is a threaded stud J which is 70 adapted to project beyond the shell. Upon the stud J is a nut K, the outer face L of which forms a seat for the inner face M of a projection M' of the shell that extends beyond the blades. Preferably the face L 80 is beveled, as shown, and also I find it desirable to form the face M slightly beveled as indicated at N. Surrounding the projection M' is a cup-shaped nut O having a threaded aperture P for engaging the stud 85 J. The inner face Q of the cup-shaped nut is also preferably beveled to engage the outer beveled face R of the projection M'. By removing the nut O the nut K may be 90 adjusted to effect a proper adjustment of the expansible portions, to obtain the desired diameter. When the nut O is turned into place the ends of the expansible portions will be tightly clamped between the two nuts. Since the base of the shell is an 95 integral, unexpansile structure, and as the outer ends of the shell are rigidly clamped against play in any direction, the reamer is made as rigid as if it were formed of an unexpansile shell.

100 It is customary to provide the reamer with bearing portions or centers at opposite ends for engaging bearings on the lathe, and these bearings must be very accurately located. With the structure described, one 105 center S for engaging the bearings of the

lathe is formed in one end of the stud and the other center T is formed in the end U of the spindle. The centers therefore are in permanent relation to each other and the adjustment of the nuts K and O does not affect the relation of the centers S and T.

What I claim as my invention is:—

1. A reamer, comprising a shank, a shell detachably mounted upon the shank, said shell being provided with a plurality of slots extending from the forward end of the shell for a portion only of its length whereby the forward end of said shell is expansible and its rear end unexpansible, and means engaging the forward end of the shell for securing the slotted portions against movement in any direction.
2. A reamer, comprising a shank, a shell detachably mounted upon the shank, said shell being provided with a plurality of slots extending from the forward end of the shell for a portion only of its length whereby the forward end of said shell is expansible, means adjustable upon the shank engaging the forward end of the shell for expanding the latter, and means coöperating with the first-mentioned means for rigidly clamping the forward end of the shell against movement.
3. A reamer, comprising a shank having a spindle at one end thereof terminating in a threaded portion, a shell upon said spindle, said shell detachably mounted being provided with a plurality of slots extending from the forward end thereof for a portion only of the length of the shell, whereby the forward end of the shell is expansible, a nut engaging said threaded portion arranged within the forward end of the shell, and a second nut also engaging said threaded portion surrounding the end of the shell and coöperating with said first-mentioned nut to rigidly clamp the forward end of the shell against movement.
4. A reamer, comprising a shank provided with a tapering spindle that terminates in a threaded stud, alined bearings respectively in one end of said shank and in the end of said threaded stud, a shell engaging said spindle having an unexpansible inner end and provided with an expansible portion at the forward end of the shell, a nut engaging said threaded stud arranged within the forward end of the shell, and a cup-shaped nut engaging said threaded stud and coöperating with the first-mentioned nut to rigidly

clamp the forward end of the shell against movement.

5. A reamer, comprising a shank provided with a spindle terminating at its forward end in a threaded stud, a shell having an unexpansible portion at its inner end and having the forward portion thereof expansible, there being a collar on said shank against which the inner end of said shell abuts, coöperating interlocking portions upon the collar and shell acting to hold the latter against rotation in relation to the shank, a nut upon the threaded stud having a part arranged within the forward end of the shell and adapted to expand the latter, a cup-shaped nut engaging the threaded stud and surrounding the forward end of the shell, said nuts coöperating to clamp the forward end of the shell against movement and acting to retain the inner end of the shell in engagement with said collar.

6. A reamer, comprising a shank, an expansible shell carried by the shank, and adjustable means for expanding the shell, said shank having centers at opposite ends thereof in permanent relation to each other in all positions of adjustment of said means.

7. A reamer, comprising a shank provided with a spindle terminating at its forward end in a threaded portion, an expansible shell carried by the shank and surrounding said spindle, and expanding nuts upon the threaded portion of the spindle for securing the forward ends of the shell in their adjusted position, a center being formed at the end of said spindle, and a co-operating center being provided at the other end of said spindle.

8. A reamer, comprising a shank, a shell upon said shank having an unexpansible portion at its inner end and having its forward portion expansible, said shank having a shoulder forming an abutment for the rear end of the shell and interlocking with said end to hold the shell against rotation, means for expanding the forward end of the shank, and means engaging the forward end of the shell, retaining the rear end thereof engaged with said collar.

In testimony whereof I affix my signature in presence of two witnesses.

STUART A. COGSDILL.
